NAIL HOLDING BUILDING COMPOSITION

Clarke F. Davis, Short Hills, N. J., assignor to
American Cyanamid & Chemical Corporation,
New York, N. Y., a corporation of Delaware

Application June 1, 1935, Serial No. 24,513

2 Claims. (Cl. 72—115)

The present invention relates to a building material.

The principal object of the invention is the provision of a light, cheap building construction unit, which will have superior nail holding qualities such as that of wood, although made primarily of a cast composition.

It has been proposed to make studding of such cementitious material as gypsum, hydraulic cement, lime or concrete, but experience has shown that units made of such composition have very poor nail holding qualities and nails driven thereto have a tendency to loosen up under any sort of vibration, while at the same time the cementitious material of which the studding is made has a tendency to crack and spall when nails are driven thereto.

It has been proposed to imbed wooden slats in such composition studding so as to take the benefit of the nail holding qualities of the wood. Experience in the field has demonstrated that this teaching is not altogether satisfactory due to the fact that such wooden inserts have the tendency to absorb water from the cementitious 25 mix cast therearound with the result that upon drying, such inserts warp and/or swell with consequent cracking of the cementitious exterior.

Experiments over a long period of time have demonstrated that a studding of cementitious material having a wood core may be very satisfactorily employed which is not subject to the above deficiency if the core is treated prior to casting the cementitious material therearound, 35 with a water-proofing composition or material to prevent water absorption.

To this end, the invention contemplates a building unit having a nail holding core of wood, nailable concrete, wood pulp or any composition 40 which has nail holding qualities more superior than that of the unit itself, coated or impregnated with water repellent material such as asphaltum compositions, pine oil, water-proof coating compositions of the synthetic resin type, 45 water-proof "Cellophane", or other sheet material such as metal foil or the like, the thus water-proofed core being encased in a cementitious material such as gypsum either with or without fibrous admixtures, hydraulic cement, lime or concrete.

The invention further consists in the novel arrangement and construction of parts more fully hereinafter shown and described in the 50 accompanying drawing.

In the drawing:

Fig. 1 is a sectional view of a building unit constructed according to this invention;

Fig. 2 is a partial perspective view showing a method of waterproofing a core;

Fig. 3 is a view similar to Fig. 2 showing an alternative method of water-proofing.

Referring now to the embodiment illustrated, a nail holding core is shown at 1 which may be of any shape and of any material which will have these qualities, although wood is preferred because of its ease of working, availability and cheapness. If the core is of a water absorbent nature, then it is suitably treated to make its exterior water repellent or water-proof and this treatment is indicated at 2. It may be immersed in a bath of any suitable water repellent compositions, either with or without heat and either at atmospheric or higher pressures, if impregnation further than at the mere surface is desired. If such water-proof compositions as asphaltum are to be used, a mere surface treatment such as by painting or the like has been found to be sufficient.

Where sheet water-proofing material is used, such as water-proof "Cellophane", metallic sheets or the like, they may be applied in the manner as in Fig. 2, where the sheet 3 is wrapped around the core 1 and the loose flap 4 made to overlie the flap 5 and suitably cemented in place as by 20 means of asphaltum, water glass or any suitable adhesive medium.

Thus treated, the core may be then placed in a suitable mold and a plastic cementitious mix capable of a set cast therearound to form an exterior 6. Due to the fact that the core has been treated to prevent water absorption, the core is thus prevented from robbing the exterior layer 6 of its water during its plastic stage, while at the same time, the core is prevented from swelling due to any water absorption.

Units so constructed should, of course, be so proportioned as to make the nail holding core near enough to the surface of the unit as to be reached by the nails driven thereto and this is 45 a matter which will be determined by the size and shape of the units and the use to which they are to be put.

When nails are driven through the cementitious material 6 into the core 1, the fact that the end 50 of the nail is securely held in the core, makes available not only such abilities attributable to the core alone, but also makes available the full nail holding abilities of the cementitious material. This would not be true if the nail were 55

permitted any amount of movement or vibration.

While in the above specification certain cementitious compositions have been mentioned as the encasing material, certain water-proofing treatment has been mentioned, and certain nail holding compositions have been enumerated, yet it is to be understood that the invention is in no wise to be limited to these particular materials as they are mentioned merely as illustrative and the invention is to be construed broadly as directed to the combination of a nail holding core which is water absorbent either due to porosity, absorption, adsorption, or its cellular nature, treated either on its superficial surface or impregnated with a material which will pre-

vent water being taken up by the core, the core and its treatment being encased in any water-containing plastic mix which will take a set.

In like manner, the unit as a whole is not to be limited to studding, but is to be construed broadly as directed to any type of construction in which the above elements occur.

I claim:

1. As an article of manufacture, a nail holding core having on its superficial surface a sheet metal material impervious to moisture, and a surrounding nail penetrable set cementitious layer.

2. The article of claim 1 in which the encasing cementitious layer is gypsum.

CLARKE F. DAVIS.
